UNITED STATES PATENT OFFICE.

ALFRED VON ZEERLEDER, OF GENEVA, SWITZERLAND, ASSIGNOR TO SOCIETE ANONYME DES ATELIERS DE SÈCHERON, OF GENEVA, SWITZERLAND.

ELECTRIC-RESISTANCE HEATER FOR MELTING-FURNACES.

1,367,442.

Specification of Letters Patent.

Patented Feb. 1, 1921.

Application filed December 22, 1919. Serial No. 346,629.

To all whom it may concern:

Be it known that I, ALFRED VON ZEERLEDER, a citizen of the Swiss Republic, and resident of Geneva, Switzerland, engineer, 5 have invented new and useful Improvements in Electric-Resistance Heaters for Melting-Furnaces, of which the following is a full, clear, and exact specification.

The present invention relates to improvements in electric resistance heaters for melting furnaces of the kind wherein a moldable heating body of a resistance material stable at high temperatures is employed in combination with embedded rod-like electrodes of 15 similar material for the supply of current to said heating body.

The object of the invention is to adapt the resistance heater to threephase current supply and to this end the resistance heating body inclosing like a jacket the melting furnace is divided into three separate segments, corresponding to the current phases, which are insulated from one another and are connected at one end to current supply poles, 25 while at the other end they terminate in a continuous annular part of the resistance heating body.

The connection of the current poles to the heating segments is effected, as in the constructions described in the specification of another patent application, by means of rod-like electrodes which extend into the mass of the said segments.

In the accompanying drawing:

35 Figure 1 is a vertical section of one form of furnace adapted for three-phase current according to the invention, and

Fig. 2 is a horizontal section thereof.

1 indicates the resistance heater of moldable resistance material stable at high temperatures, which, with the interposition of the electrically non-conducting layer 2^a, incloses the melting crucible 2, and which is divided into three separate segments corresponding to the three phases of the current.

The said segments of the heating body terminate at their lower ends in a continuous annular part 1^a of the resistance heating body and at the upper part they are electrically connected to the three current supply poles 3.

The entrance and exit of the current take place at the current supply poles 3, while the annular part 1^a constitutes the common connection of the three-phase circuit which can be connected to the transformer.

The connection of the current poles 3 with the heater segments is effected through the medium of the rod-like electrodes 4, which extend far enough into the mass of the said segments to insure a permanent efficient transfer of current at these parts.

The heating segments 1 are insulated from one another over their whole length by means of insulating ribs or partitions 5 which engage between them and are for example constituted of masonry; as an additional means of insuring their mutual insulation vertical insulating plates 7, of mica or asbestos, for example, may be inserted 70 through the said ribs and the masonry jacket 6, although such insulating plates are not absolutely necessary.

What I claim is:

1. In an electrical resistance heater for melting furnaces, adapted for threephase current supply, the combination with a melting crucible of a heating body of stable resistance material surrounding the melting crucible, said heating body being divided 80 into three separate segments corresponding to the current phases, electrically insulating partitions being arranged between said segments and the latter being connected at one end to current supply poles, while at the 85 other end they terminate in a continuous annular part of the resistance heating body, substantially as described.

2. In an electrical resistance heater for melting furnaces, adapted for threephase current supply, the combination with a melting crucible of a heating body of stable resistance material surrounding the melting crucible and an intermediate electrically non-conducting layer, said heating body being divided into three separate segments corresponding to the current phases, electrically insulating partitions being arranged between said segments and the latter being connected at one end to current supply poles, 95 while at the other end they terminate in a continuous annular part of the resistance heating body, substantially as described.

In witness whereof I have hereunto signed my name this 28 day of November, 1919, in 105 the presence of two subscribing witnesses.

Dr. ALFRED VON ZEERLEDER.

Witnesses:

LOUIS MUNICE,
Z. GUILLOUX.
